SYRINGE SET

Thomas W. Miller, Ashland, Ohio, assignor to
 The Faultless Rubber Company, Ashland, Ohio,
 a corporation of Ohio

Application July 1, 1932, Serial No. 620,415

6 Claims. (Cl. 128—227)

This invention relates to syringe sets, and particularly, to means for carrying on the syringe bag the spare nozzles or pipes comprised in such sets, and has for an object the provision of a new and improved article of this character.

In the drawing accompanying this specification and forming a part of this application I have shown, for purposes of illustration, one embodiment which my invention may assume, and in the drawing:

Figure 1 is a side view of this embodiment, partly in elevation and partly in section, while

Figure 2 is a horizontal sectional view corresponding substantially to the line 2—2 of Figure 1.

The embodiment of the invention herein disclosed comprises a syringe bag 10 (not completely shown) as used in connection with a fountain syringe or the like, as is well-known in the art, and comprising integral front and rear walls 11 and 12 restricted as indicated at 13 to form an elliptical mouth 14 beyond which the rear wall 12 is continued to provide a perforated ear portion 15 by which the device may be suspended.

Disposed at the ends 16 of the mouth 14 are clamps 17 formed of resilient rubber and each having resilient jaws 18 and 19 cooperating to resiliently retain a nozzle 20 therebetween, and to support the walls 11 and 12 forming the elliptical mouth 14. The jaw 18 is slightly larger than the jaw 19, and is cemented to the back wall 12 of the receptacle 10, while the jaw 19 is free, to prevent injury upon stretching of the receptacle. Each clamp 17 has a depressed seat 21 into which the shank portion 22 of the nozzle 20 is adapted to rest while the jaws 18 and 19 detachably embrace the reduced portion 23 of the nozzle 20.

The nozzles 20 when so secured in the receptacle 10 are disposed substantially out of sight and accordingly do not detract from the appearance of the bag. On the other hand, they are mounted within the bag, and therefore will not be mislaid.

Not more than one of the several nozzles usually supplied with a fountain syringe can at any given time be operatively secured to the syringe and accordingly the others, unattached, are easily misplaced or lost, or in any event, are not at hand when needed.

My invention corrects this by providing the clamps 17 on the bag 10, so that the spare nozzles can be detachably secured directly to the receptacle 10 itself, and therefore will not be

misplaced or lost, and consequently, will always be at hand when needed.

It will be apparent to those skilled in the art that the embodiment herein disclosed accomplishes at least the principal object of the invention, and that the construction is adaptable to a wide variety of uses, and embodies advantages other than those herein disclosed, and also that the embodiment may be variously changed and modified without departing from the spirit or scope of the invention, and accordingly it will be understood that the above disclosure is illustrative only, and that my invention is not limited thereto.

I claim:

1. A syringe set, comprising: a syringe bag for containing fluid, and adapted to communicate with a discharge tube; a discharge nozzle adapted to be connected to the discharge end of said discharge tube; and a nozzle support secured interiorly of said bag and including a portion fixed to one wall of said bag, and a curved resilient portion free of said bag, said support being operable to clamp said nozzle to support the same substantially within said bag.

2. A syringe set, comprising: a syringe bag for containing fluid and adapted to communicate with a discharge tube; a discharge nozzle adapted to be connected to the discharge end of said discharge tube; and a nozzle support secured interiorly of said bag and including a portion fixed to one wall of said bag, and a curved resilient portion free of said bag, said support being operable to clamp said nozzle to support the same substantially within said bag, said support being constructed and positioned to hold the mouth of said bag distended.

3. A syringe set, comprising: a syringe bag of collapsible material, for containing fluid, and adapted to communicate with a discharge tube; a discharge nozzle adapted to be connected to the discharge end of said discharge tube; and a nozzle support secured interiorly of said bag and adjacent to the mouth of said bag, and having means operable to support said nozzle substantially within said bag, but in a position accessible at the mouth of said bag for convenient removal, said support having means extending between the walls of said bag at the mouth thereof, and serving to hold the mouth of said bag distended.

4. A syringe bag of flexible material having a collapsible mouth through which said bag may be supplied with liquid, said bag being usable with detachable nozzle discharge means; and supporting means for said nozzle discharge means,

said supporting means extending into the mouth of said bag and operable to hold the mouth of said bag at least partly open, and to support said nozzle discharge means in a position as to be substantially concealed within said bag when not in use.

5. A syringe bag of flexible material having a collapsible mouth through which said bag may be supplied with liquid, said bag being usable 10 with detachable nozzle discharge means; and supporting means for said nozzle discharge means, said supporting means extending into the mouth of said bag and operable to hold the mouth of said bag at least partly open, and to support said 15 nozzle discharge means in a position as to be substantially concealed within said bag when not in use, said supporting means being constructed and arranged to hold the mouth of said bag

partly open even though no nozzle discharge means are present therein.

6. A syringe bag of flexible material having a collapsible mouth through which said bag may be supplied with liquid, said bag being usable 5 with a plurality of different sized detachable nozzle discharge means; and a plurality of different sized supporting means for said nozzle discharge means, said supporting means being spaced along the mouth of said bag, and extending into said 10 mouth, and constructed and arranged to hold the mouth of said bag at least partly open throughout its extent, and operable to support said one or more of said nozzle discharge means 15 in a position to be substantially concealed within said bag when not in use.

THOMAS W. MILLER.
